Inventor:
Edward A. Cuniff
by Edward P. Allen
Atty.

UNITED STATES PATENT OFFICE.

EDWARD A. CUNNIFF, OF WALTHAM, MASSACHUSETTS.

ATTACHMENT FOR LOOM TEMPLES.

Application filed December 8, 1925. Serial No. 74,187.

To all whom it may concern:

Be it known that I, EDWARD A. CUNNIFF, a citizen of the United States of America, and a resident of Waltham, in the county 5 of Middlesex and Commonwealth of Massachusetts, have invented certain new and useful Improvements in Attachments for Loom Temples, of which the following is a specification.

10 This invention relates to loom temples, and more particularly to means whereby they may be freely and safely lubricated so that the cloth or fabric in the loom may be fully protected from oil emanating from 15 the temples which would otherwise spatter thereover.

It is an object of the invention to provide simple and inexpensive means whereby existing loom temples, certain parts of 20 which had heretofore been operating without lubrication because of the danger of spattering oil on the cloth, may be well lubricated and the cloth fully protected from damage therefrom.

25 Other objects of the invention will be fully understood from a description of the drawings and the claims hereinafter given.

Of the drawings:

Figure 1 represents a top plan view of 30 a well known loom temple having the invention applied thereto.

Figure 2 is a top plan view of certain portions of the temple shown in Figure 1 as it appears prior to applying the invention thereto.

Figure 3 is a section on the line 3—3 Figure 1.

Figure 4 is an elevation of the guard or cover removed from the temple, and looking in the direction of the arrow A Figure 3.

Figure 5 is a view of the guard or cover looking toward the right Figure 4.

Figure 6 is a top plan view of another well known temple having the invention applied thereto.

Figure 7 is a top plan view of certain parts of the temple shown in Figure 6 but showing the cap of the guard or cover removed.

Figure 8 is a section on the line 8—8 Figure 6.

Figure 9 is a section on the line 9—9 Figure 6.

Figure 10 is a view of the guard as it 55 would appear when detached from Figure 7.

Figure 11 is a front view of the lower part of the guard detached.

Figure 12 is an elevation of the guard 60 cover or cap detached and looking in the direction of arrow B Figure 6.

Like characters represent like parts 65 throughout the several figures of the drawings.

Referring to the drawings:

The drawings herewith illustrate two forms of the guard or protective device which might be used but it will be understood that it is not the intention to limit the invention to the precise construction and arrangement shown as various changes might be made therein without departing from its spirit and scope.

The temples illustrated herein are two of 75 the best known and most widely used and therefore afford excellent subjects to which to apply the present invention.

Figures 1 to 5 inclusive of the drawings 80 illustrate a temple having a bracket 10 arranged to be secured to the breast beam of a loom, the said bracket having guideways 11 and 12 thereon to slidably receive the bar 13 which carries the temple head or pod 14.

The said bar 13 is arched at 15 to correspond to a like depression 16 in the bracket 10 which arrangement conveniently houses the spring 17 one end of which abuts a boss 18, see dotted lines Figure 2, upstanding 90 from the bracket 10, the other end abutting a lug 19 depending from the bar 13, see also Figure 3.

The bar 13 is slidably held in place by a hold down member 20 which is held to the bracket 10 by means of a screw 21 entering the boss 18 and a screw 22 entering another boss 23 upstanding from the bracket 10.

The bar 13 is slotted at 24 and 25 to accommodate the screws 21 and 22, so that it may be moved forwardly by the lay against the action 17, which normally holds the bar with its lug 19 in contact with the boss 23.

The arrangement just explained is well known and its popularity is such that many thousand of these temples are in use, and

undoubtedly many more would be used but for the fact that when the slide and slide-ways have been sufficiently lubricated to prevent wear, the cloth or fabric in the 5 loom would invariably become spattered with oil and consequently unmarketable.

Because of the trouble occasioned by the spattering of oil it has been necessary to discontinue the lubrication of the slide, or 10 at least to such extent that spattering thereof ceased, and it has been found that the limited quantity of oil or lubricant that could be used was not sufficient to prevent wear, and therefore the great majority of temples 15 were operated with little or no lubrication, to their detriment.

It is an object of the present invention to provide means easily applied to existing temples, by the use of which they may be 20 freely and sufficiently lubricated, without fear of spattering the cloth, thus prolonging the life and usefulness thereof.

The invention contemplates the use of a guard or cover for certain parts of the 25 temple which should be lubricated, particularly those parts of the sliding bar 13 and the hold down member 20 closest to the cloth or fabric F, the selvage of which is indicated by the dot and dash line X—X of 30 Figure 1, and at the rear portion of the bracket 10 where a portion of the bar 13 terminates and is ordinarily exposed to view, and from which location drops of oil would 35 be forced when the lug 19 was forceably caused to contact with the boss 23 by the spring 17 when the day recedes from contact with the temple heel 26.

The guard or cover 27 is preferably made 40 of one piece of thin but stiff metal either cast or struck up, and shaped to form two chambers, which in the present instance communicate with each other, and in which a fibrous material such as cotton waste or 45 batting is housed.

The guard 27 has a top portion 28, a deep side portion 29, two short side portions 30 and 31, and a rear end and bottom portion 32 and 33 respectively.

A portion of the top 28 and the side portion 30 form a chamber 34 for the housing 50 of fibrous material 35, while another portion of the said top, and the side, end, and bottom portions 29, 32 and 33 respectively form another chamber 36 for the housing of 55 fibrous material.

The top 28 is provided with holes through which the screws 21 and 22 pass thus obviating the necessity of providing other fastening means for the cover 27; and other 60 holes 38 and 39 may be provided in the said top 28 for the entrance of a screw driver to engage the screws which secure the bracket 10 to the breast beam, not shown.

From the foregoing it will be readily seen 65 that the guard or cover may be made of a

shape to suit the particular temple with which it is to be used, and that with its use, the guides and slides may be freely lubricated as the fibrous material will catch and hold any oil that may be splashed or ejected by 70 the moving parts.

Figures 6 to 11 inclusive show the invention arranged to be applied to another well known and popular temple wherein the bar 13* has sliding contact with the base or bracket 10*, which is intended to be secured to the breast beam not shown, and the cover or hold down 20*.

The said bar 13*, as will be seen by viewing Figure 6 of the drawings, extends rearwardly beyond the said bracket 10* and the said cover 20* so that if the above referred to contacting parts were lubricated, it will be readily seen that oil would be ejected from the bar housing or cover, and would 80 spatter over the cloth in the loom.

In this temple a fair amount of protection is offered by the cover 20*, but the opening at the rear of the housing through which the bar 13* extends is the troublesome point, 90 and particularly on the side nearest the cloth the selvage of which is indicated by the dot and dash line Y—Y Figure 6.

In this instance a two-part guard is made having a bottom 33*, a rear wall 32*, a side wall 29*, and a front wall 40, arranged to provide a chamber 34*, which extends partly across the rear of the bar housing and partly along the inner side thereof, for the reception of fibrous material 35*, and having a cover 28* secured thereto by a bolt 41 which passes through holes in the hold down 20* already provided.

It will be understood that dependence is not placed upon the close fit of the guard members to the temple to prevent the spattering of oil, but rather to the fact that the guard functions as a holding means for the fibrous material which catches and holds the oil when it spatters, thus preventing it from 105 passing outwardly of the guard, and onto the cloth.

Having described the invention I claim:

1. As an article of manufacture, a guard member arranged to be attached to existing loom temples, and arranged to hold a quantity of fibrous material whereby lubricant spattered by a loom temple will be caught and held by said fibrous material.

2. As an article of manufacture, a guard member comprising a hollow body portion arranged to form a chamber for the reception of fibrous material to catch and hold oil spattered by a loom temple, and arranged to be secured to existing loom temples by 125 existing securing devices.

3. The combination of a loom temple and a hollow bodied attachment therefor arranged to be secured to said temple and to receive a quantity of fibrous material where-

by oil ejected from said temple during the operation thereof will be caught and held by said material.

4. The combination of a loom temple having exposed slide bearings from which lubricant may be ejected during the operation thereof, and a guard for said bearings comprising a thin metallic body arranged to be secured to the temple by existing means, and in conjunction therewith to provide a chamber for the reception of fibrous material whereby lubricant ejected from said bearings will be caught and held by said fibrous material.
- 10 5. The combination of a loom temple hav-

ing exposed slide bearings from which lubricant may be ejected during the operation thereof, and a guard for said bearings comprising a thin metallic body arranged to be secured to the temple on the cloth side thereof by existing screws, and in conjunction with said temple arranged to form a chamber for the reception of fibrous material, and fibrous material in said chamber whereby lubricant ejected from said bearings will be 20 25 caught and held by said material.

Signed by me at Boston, Massachusetts, this 5th day of December, 1925.

EDWARD A. CUNNIFF.
